UNITED STATES PATENT OFFICE.

ARCHIE H. STRONG, OF WEST BRIGHTON, NEW YORK.

TOBACCO-PIPE.

1,170,465.

Specification of Letters Patent.

Patented Feb. 1, 1916.

Application filed November 19, 1914. Serial No. 872,997.

To all whom it may concern:

Be it known that I, ARCHIE H. STRONG, a subject of the King of Great Britain and Ireland, and residing at West Brighton, 5 county of Richmond, and State of New York, have invented a certain new and useful Improvement in Tobacco-Pipes, of which the following is a specification.

The present invention relates to tobacco 10 pipes and the object of my invention is to provide a pipe of novel construction, having among other features of advantage, a bowl lining of novel character which serves to ameliorate the unpleasant flavor of the pipe 15 when new, and by reason of its ready removability and its inherent characteristics, facilitates the effective cleaning of the pipe.

In the accompanying drawings, Figure 1 20 is a longitudinal section through a pipe in which my invention is embodied in one form; Fig. 2 is a dropped and broken perspective of the elements which form the pipe bowl; and Fig. 3 is a plan of the blank from which the absorbent wafer is formed.

As is well known to smokers, the ordinary 25 wooden-bowl pipe is objectionable when new by reason of the unpleasant fumes which are given off by the wood of the pipe bowl when the pipe is first smoked. It is not until the pipe has been well "aged" or "broken in" and the interior of the pipe bowl substantially carbonized and the surfaces of the 30 passages through which the smoke is led to the mouth piece impregnated by smoke or 35 tobacco juices, that comfortable enjoyment of the pipe is attained. To obviate this defect I now propose to provide the bowl with a carbon lining which not only insures a sweet smoke, while the pipe is still new, but 40 also affords a hard surface for the pipe bowl which may therefore be completely and thoroughly cleaned without danger of injury to the "crust" and yet at the same time is absorbent of the tobacco juices and 45 consequently full flavored. Preferably the lining is so secured in position as to be readily removable for cleaning or renewal.

In the form here shown the present pipe 50 comprises a bowl portion 5 with an offset stem 6 longitudinally bored to receive the mouth piece 7, through the passage 8 in which communication is established with the well 9 at the bottom of the bowl. The interior of the bowl is bored out through the 55 major part of its depth to abnormal diameter at 10 leaving however a shoulder 11 in

the lower portion thereof to form a seat. Upon the latter rests a metallic disk 12 perforated to permit the passage of smoke therethrough. A cylindrical section of carbon tubing 13 rests upon the upper face of the disk 12 and forms a lining for practically the entire depth of the bowl. It is held in position by a screw cap 14, the central aperture of which is substantially identical in diameter with the internal diameter of the tube section 13. The shoulder 15 of the screw cap rests upon the upper end of the tube 13 and the threaded engagement 16 between the pipe bowl 5 and the screw 70 cap 14 enables the latter to be screwed down with a clamping action upon the carbon 13 so that the latter is held in position.

The internal diameter of the recess 10 in the pipe bowl preferably exceeds the overall 75 diameter of the carbon tube 13 and thus leaves a space 17 surrounding the latter within which the juices of the tobacco which permeate the tube may gather. Without this space the tube would soon become practically cemented to the pipe bowl by the permeating sticky juices of the tobacco and thus prevent the ready removal of the tube for 80 cleaning. Positioning offsets 18, 19, may be provided however to engage the tube snugly 85 at top and bottom and thus hold the same accurately in register with the central aperture in the screw cap and the walls of the well 9.

I have found it advantageous to provide 90 an absorbent in the well 9 and a convenient form of this is shown in the wafer 20 located beneath the screen 12. This wafer 20 may not only serve to take up the nicotine from the tobacco, but also may act as a 95 vehicle for an antiseptic, a perfume or flavoring matter adapted to be freed under the conditions existing when the pipe is smoked. As here shown the wafer 20 is shaped as a disk of less diameter than the 100 interior of the well but underlying the holes in the screen 12 and supported through downwardly struck legs 21 which rest in the bottom of the well. The wafer 19 may be readily thrown out and replaced after the 105 cap 14 is unscrewed and the tube 13 and screen 12 lifted out.

The pipe is particularly useful in connection with tobacco which is marketed in cartridge form so that a "charge" may be 110 bodily inserted in the pipe bowl ready for smoking. Such cartridges cannot ordi-

narily be used, since the inner face of the pipe bowl soon becomes roughened and more or less irregular by reason of the charring and caking of the burnt tobacco against the 5 sides of the pipe bowl and this crust cannot be removed without affecting the flavor of the pipe. The present pipe bowl may be scraped clean readily and without injury to the flavor of the pipe, so that its inner face 10 is kept smooth and perfectly cylindrical. The tobacco cartridges may be slipped easily into position therein and the screen 12 affords a bottom against which the cartridge may be firmly pressed down while at the 15 same time preventing its entry into the pipe well 9 and thus the clogging of the draft passage 8 leading to the mouth piece.

In the particular pipe here shown I have made the stem straight so that core 22 of the 20 mouth piece 7 may be extended completely to the well 9 of the pipe bowl. This prevents the leakage of the tobacco juices at the joint 23 between the pipe stem and the mouth piece.

25 The particular shape of the pipe bowl may be varied to suit individual tastes and the proportions may be as desired. I prefer however to have the inner diameter of the carbon tube 13 of standard $\frac{3}{4}$ " internal diameter for pipe bowls. While I have stated 30 that the tube 13 may be readily cleaned, some may prefer to renew it frequently and

this may be done economically, since the tube sections can be produced as a standard article at very low cost.

35

I claim as my invention:—

1. A tobacco pipe having a bowl portion, a removable carbon tube section forming a lining therefor, and a retaining cap overlying said tube section and engaging said pipe 40 bowl to hold said lining in position therein, said tube section being spaced from the surrounding walls of the bowl throughout at least the major portion of its depth.

2. A tobacco pipe having a wooden bowl 45 portion shouldered adjacent the bottom of the bowl well, a screen supported on said shoulder, a tubular carbon lining resting freely at its lower end on said screen, and a wooden retaining ring shouldered on its inner face to engage the upper end of said tubular lining and having a threaded engagement with the body of the bowl, the inner diameter of said ring being substantially the same as that of said lining and 50 registering therewith in the assembled condition of the parts.

55 In testimony whereof I have signed my name to this specification, in the presence of two subscribing witnesses.

ARCHIE H. STRONG.
